UNITED STATES PATENT OFFICE.

FRANK C. WHITE, OF WOODBURY, NEW JERSEY.

BOTTLE-STOPPER.

SPECIFICATION forming part of Letters Patent No. 337,541, dated March 9, 1886.

Application filed January 8, 1886. Serial No. 187,997. (No model.)

To all whom it may concern:

Be it known that I, FRANK C. WHITE, of Woodbury, in the county of Gloucester and State of New Jersey, have invented a new and useful Improvement in Bottle-Stoppers, of which the following is a specification, reference being had to the annexed drawings, forming a part thereof, in which—

Figure 1 is a side elevation of a part of a bottle, showing the application of my improvement. Fig. 2 is a plan view of a bottle-stopper, showing the neck of the bottle in section.

Similar letters of reference indicate corresponding parts in both figures of the drawings.

The object of my invention is to provide a simple, secure, inexpensive, and easily-operated stopper for bottles containing effervescent liquids; and it consists in the combination, with a bottle having lugs formed on or attached to the opposite sides of the neck thereof, of a ring surrounding the bottle-neck provided with spiral cams and diametrically-opposite offsets, and arranged to engage the lugs projecting therefrom, and a bail carrying an elastic stopper, and having its ends received in opposite sides of the ring.

The neck A of the bottle to which my improved stopper is applied is provided on diametrically opposite sides, and at a short distance from the mouth of the bottle, with short lugs a, which are preferably formed in the process of blowing the bottle. A ring B, surrounds the bottle-neck below the lugs a, and is provided on its upper edge with two oppositely-arranged spiral cams, b, terminating at their higher ends at the stops c, and beginning at the lower ends at the offsets d, which are formed in diametrically-opposite sides of the ring B to permit of slipping the ring over the lugs a on the sides of the bottle-neck.

To the mouth of the bottle is fitted an elastic stopper, C, formed of the plate e, having on the top thereof the stud f, and provided on its under surface with a stud for receiving and retaining the elastic ring g. A bail, D, having its ends turned inward at right angles and entering holes in the offset portions of the

ring B, has in the middle thereof a loop, h, which receives the stud f projecting from the upper surface of the plate e. The ends of the bail which project into the offset portions of the ring B reach nearly or quite to the bottle-neck, so that when the ring B is in position on the neck of the bottle the inwardly-projecting ends of the bail will engage the lugs a when the offset parts of the ring B are opposite the lugs, and will prevent the ring from slipping from the neck of the bottle. The ring B is put in its position on the bottle when the bail D is detached from it, and by inserting the ends of the bail D in their place in the ring the ring will be secure. The stopper C is clamped in its place in the mouth of the bottle by bringing the spiral cams b, formed on the ring B, into engagement with the lugs a on opposite sides of the neck, and turning the ring under the lugs, causing it to draw the bail D downward and force the stopper C into the mouth of the bottle. The stopper is released by turning the ring B in the opposite direction and then swinging the bail to one side, as shown in Fig. 2.

Having thus described my invention, what I claim as new, and desire to secure by Letters Patent, is—

1. The combination, with a bottle-neck provided with the lugs a, of the ring B, having the spiral cams b formed thereon, and provided with offsets d, the bail D, and the elastic stopper C, substantially as herein shown and described.

2. The combination of the ring B, having formed thereon the spiral cams b, and provided with offsets d, the bail D, having its ends bent inward and passing into the offsets d, the elastic stopper C, formed of the plate e and the soft rubber ring g, and the bottle A, provided with lugs a, substantially as herein shown and described.

FRANK C. WHITE.
